CLAIM

The ornamental design for a humidifier assembly, as shown and described.

DESCRIPTION

FIG. 1 is a front perspective view of a humidifier assembly according to an embodiment of our design;

FIG. 2 is a top view thereof;

FIG. 3 is a front view thereof;

FIG. 4 is a right side view thereof; and,

FIG. 5 is a rear view thereof.

Throughout the various figures of the drawings, certain views may not be provided. The omission of a particular view is intended to convey that the element(s) depicted is/are plain and/or unornamented in that view.
